UNITED STATES PATENT OFFICE.

HOWARD PRICE COOK, OF CLEARLAKE, TEXAS.

SHAVING-CUP.

No. 926,805.

Specification of Letters Patent.

Patented July 6, 1909.

Application filed December 28, 1908. Serial No. 469,515.

To all whom it may concern:

Be it known that I, HOWARD P. COOK, a citizen of the United States, residing at Clearlake, in the county of Collin and State of Texas, have invented a new and useful Shaving-Cup, of which the following is a specification.

This invention relates to improvements in shaving mugs, and has for one of its objects the provision of a device of that kind having a compartment separated from the soap compartment, which is adapted to be filled with water and so arranged that the water may be supplied to the soap compartment at will.

A further object is the provision of a drain leading from the soap compartment to the water compartment whereby the former may be drained of excess water after the lather has been formed.

With these and other objects in view, as will hereinafter more fully appear, the invention consists in the novel construction and arrangement of parts hereinafter described, delineated in the accompanying drawings, and particularly pointed out in that portion of this instrument wherein patentable novelty is claimed for certain distinctive and peculiar features of the device, it being understood that, within the scope of what hereinafter is thus claimed, divers changes in the form, proportions, size, and minor details of the structure may be made, without departing from the spirit or sacrificing any of the advantages of the invention.

In the accompanying drawings forming part of this specification:—Figure 1 is a vertical sectional view of the device. Fig. 2 is a plan view of the same.

Similar numerals of reference are employed to designate corresponding parts throughout.

In carrying out the invention I provide a shaving cup with a false bottom which divides the interior of the cup into two compartments. The upper of these compartments is designed to hold the soap, and the lower to be filled with water. Communication is established between the compartments through the false bottom, the construction being such that when the cup is tilted the water from the lower compartment will flow into the upper and there mingle with the soap. The lather is formed in the usual way with a brush and after the lather has

reached the required consistency the cup is permitted to resume a horizontal position, whereby the excess water will drain from the soap compartment back into the water compartment.

60

The advantages gained by this construction are at once obvious, since it is well known that considerable difficulty is experienced in maintaining the lather at a uniform heat. Heretofore it has been, in most cases, 65 customary to put a supply of water into the shaving cup; after the lather had been formed and the excess water drained out of the cup the lather would hold its original temperature for a short time only; in order 70 to again bring the lather to the required temperature it being necessary to add a new supply of heated water from a detached source. As before stated the present invention remedies this disadvantage by providing a water 75 compartment which will maintain the heated lather at substantially its original temperature throughout the operation of shaving.

The cup 1 may be of any desired shape and formed of any suitable material. In the present instance it is shown to consist of a hollow cylindrical metallic body, the outer surface of which is provided with a suitable handle 2. Medially disposed within the cup is a false bottom 3, the edge of which is suitably secured to the inner surface of the cup 1. Thus it can be seen that by the provision of the false bottom 3 the interior of the cup is divided into an upper and a lower compartment, the functions of which have already been described. Communication is established between the compartments by means of an opening 4 disposed in the edge of the false bottom 3. The function of this opening is two-fold; in the first place, the water which is poured into the upper compartment will find its way through the opening 4 into the lower compartment whereby the latter will be filled, and in the second place, after the water compartment has been 100 filled, and the cup tilted in the proper direction the water from the water compartment will flow through the opening 4 into the soap compartment.

Diametrically disposed to the opening 4 105 is what will subsequently be termed a vent opening 5, formed in the edge of the false bottom 3. The vent opening is surrounded by one end of a vertically disposed pipe 6 the opposite end of which extends to a point 110

substantially coincident with the upper edge of the mug. The pipe 6 is substantially semi-circular in shape and has its sides secured to the inner surface of the mug, it being understood that the vent opening 5 will be identical in shape to the pipe 6 so that the inner face of the latter will be coincident with the wall of the opening. The function of the vent pipe will be readily understood and a further description of the same is not deemed necessary.

From the foregoing it will be seen that I have provided a device which is simple in construction and comparatively inexpensive to manufacture. It can be further seen that almost any form of metallic shaving mug may be readily fitted with the construction

hereinbefore described, without changing the shape of said mug.

What is claimed is:—

A shaving mug interiorly divided into an upper and a lower compartment by a medially disposed false bottom, said bottom being provided with an opening communicating with said compartments, and further provided with a vent having an outlet in a plane with the upper edge of said mug.

In testimony that I claim the foregoing as my own, I have hereto affixed my signature in the presence of two witnesses.

HOWARD PRICE COOK.
